UNITED STATES PATENT OFFICE

2,547,642

ADJUSTABLE BED TABLE

Helen E. Heuser, Detroit, Mich., assignor of one-half to Henri E. Heuser, Detroit, Mich.

Application May 25, 1946, Serial No. 672,289

3 Claims. (Cl. 311—27)

1

The present invention relates to new and useful improvements in articles of furniture and more particularly to a portable table adapted primarily for use in hospitals or by bedridden persons for the purpose of providing a table which will bridge the bed and provide a convenient support for food trays and other articles needed in the care and comfort of the sick as well as to provide a writing table.

An important object of the present invention is to provide a bed table including means for adjusting the table longitudinally for conveniently straddling or bridging a bed or for collapsing into a compact form when not in use as a bed table and also embodying a construction whereby the device may be used as a desk or table.

A further object of the invention is to provide a device of this character of simple and practical construction, which is neat and attractive in appearance, strong and durable in use, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a perspective view showing the device in use as a bed table.

Figure 2 is an enlarged transverse sectional view showing the table top supported in a slide position for use as a reading table.

Figure 3 is a perspective view.

Figure 4 is a plan view of one of the longitudinal frame members of the table with the table top removed.

Figure 5 is a longitudinal sectional view.

Figure 6 is an enlarged sectional view of one of the adjustable legs taken on a line 6—6 of Figure 5.

Figure 7 is a view in elevation of the upper portion of one of the adjustable legs.

Figure 8 is a sectional view taken on a line 8—8 of Figure 7, and

Figure 9 is a view in elevation of the lower end of the legs at one side of the table.

Referring now to the drawings in detail, wherein for the purpose of illustration I have disclosed a preferred embodiment of the invention the numeral 5 designates a pair of U-shaped leg members constructed of lightweight metal tubing and in the upper ends of which leg extensions 6 are received for vertical adjustment and secured in vertically adjusted positions by means of pins

2

7 inserted transversely through the upper ends of the legs 5 and through vertically spaced openings 8 in the leg extensions 6.

The upper ends of the extensions 6 are threaded into the lower downturned ends 9 of longitudinal frame members 10 which project inwardly at the front and rear of the table. The frames 10 are slidably received in the ends of front and rear tubes 11 and 12 which are secured to the underside of a table top designated generally at 13 by means of collars 14 having flanges 15 secured to the underside of the table top.

The front and rear sleeves 11 and 12 are formed with longitudinally extending slots 16 through which set screws 17 project for sliding movement in the slots, the set screws being threaded in the frames 10, said screws functioning as stops to limit the outward adjusting movement of the frames 10 in the sleeves.

20 The table top 13 includes a lower plate 18 and an upper plate 19, the plate 19 being hingedly connected to the lower plate 18 along one longitudinal edge by a conventional form of hinge structure 20 whereby the upper plate 19 may be swung vertically into an upwardly inclined position as shown in Figure 2 of the drawings. The underside of the plate 19 is formed with a plurality of notches 21 adapted for selectively receiving the free end of a prop 22 hinged at its other end as indicated at 23 to the rear edge of the bottom plate 13. The front edge of the plate 19 is formed with an upstanding flange 24 to provide a rest for articles when the upper plate 19 is in its raised position.

25 Front and rear longitudinal plates 25 and 26 are secured to the front and rear edges respectively of the table top 13 to extend downwardly therefrom to form front and rear skirts for the table top and side plates 27 are secured to the downturned ends 9 of the frames 10 to likewise form skirts at the side edges of the table top when the legs 5 are moved inwardly as shown by the full lines in Figure 3 of the drawings. When the legs 5 are moved into their inward position the table may thus be used as an article of furniture in a room, such as a writing desk or table and when it is desired to use the table as an over-the-bed table the legs 5 are moved outwardly into a position to straddle or bridge a bed 28 as shown in Figure 1. The side or end plates 27 may then be used as a towel rack for the table.

In view of the foregoing description taken in conjunction with the accompanying drawings it is believed that a clear understanding of the construction, operation and advantages of the

device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim as my invention:

1. A bed table comprising a substantially flat elongated panel of a length less than the width of a bed, a pair of tubular guides fixed to the panel, a pair of substantially L-shaped members associated with each of the guides, the longer legs of said L-shaped members being slidably received in said guides and supporting laterally projecting fasteners, said guides having longitudinal slots receiving said fasteners, tubular extensions detachably secured to the shorter legs of said L-shaped members and having a plurality of longitudinally spaced apertures, a pair of U-shaped supports having terminal sockets slidably receiving the extensions, locking members removably carried by said supports and positionable in selected of the apertures in said extensions for vertical adjustment of the panel, forward and rear skirt forming members secured to and depending from the panel, and side skirt forming members fixed to the shorter legs of said L-shaped members abutting the ends of said forward and rear skirt forming members when the L-shaped members are in contracted position and forming article racks when the L-shaped members are in extended position.

2. A bed table comprising a table top, a pair of guides secured to the undersurface of said table top, a pair of L-shaped members carried by each of said guides, the longer legs of said members being slidably received in said guides and the shorter legs of said members depending from the guides, a pair of side walls fixed to the shorter

legs of said members, and a pair of U-shaped side members adjustably connected to the shorter legs of said L-shaped members.

3. A bed table comprising a table top, a pair of guides secured to the undersurface of said table top, a pair of L-shaped members carried by each of said guides, the longer legs of said members being slidably received in said guides and the shorter legs of said members depending from the guides, a pair of side walls fixed to the shorter legs of said members, a pair of U-shaped side members, posts detachably secured to the shorter legs of said L-shaped members, said side members slidably supporting said posts, and means adjustably securing said posts to said side members for vertically adjusting the table top.

HELEN E. HEUSER.
